RADIATION MONITORING BADGE

James E. Leone, Quincy, Mass., assignor to Tracerlab,
Inc., Waltham, Mass., a corporation of Massachusetts

Filed Dec. 15, 1958, Ser. No. 53,775

Term of patent 14 years

(Cl. D29—2)

FIG. 1

FIG. 2

FIG. 3

Fig. 1 is a perspective view of a radiation monitoring badge showing my new design;

Fig. 2 is a right side elevational view thereof;

Fig. 3 is a rear elevational view thereof.

The dominant features of my design reside in the portions shown in full lines.

I claim:

The ornamental design for a radiation monitoring badge, substantially as shown and described.
